UNITED STATES PATENT OFFICE.

CHARLES EDMUND CLEWS, OF PAEROA, NEW ZEALAND.

CLAMPING DEVICE.

1,273,741.

Specification of Letters Patent. Patented July 23, 1918.

Application filed August 5, 1916. Serial No. 113,306.

To all whom it may concern:

Be it known that I, CHARLES EDMUND CLEWS, a citizen of the Dominion of New Zealand, and residing at Paeroa, in the 5 Provincial District of Auckland, in the Dominion of New Zealand, carpenter, have invented certain new and useful Improvements in Clamping Devices, of which the following is a specification.

10 This invention relates to clamping devices more particularly intended for use in clamping the filter cloths to the frames of vacuum filters employed in the process of saving gold.

15 Heretofore the cloths have usually been fixed to the frame by means of battens and bolts, the edges of the cloth being clamped between the battens and the frame. This construction had drawbacks, which the

20 present invention overcomes.

The invention comprises two bent levers, pivoted at opposite ends of a cross-bar, and a cam pivoted in slots formed in the overlapping ends of the said levers. Grooves 25 are formed near the other ends of the levers to fit upon rods adapted to be pressed into grooves formed in the filter frame. The cloths are interposed between the rods and the grooves, and thus make a tight 30 joint and are securely held in position, when the cam is operated by its lever.

The drawing herewith illustrates the invention as employed to clamp the filter cloths to a filter frame, and will now be referred to for the purposes of a detailed 35 description:—

Figure 1, is a side elevation,

Fig. 2, a front elevation, and

Fig. 3, a plan of the apparatus.

40 The bent levers 1 and 2 are fulcrumed by pins 3 and 4 respectively to a crossbar 5. The horizontal members of the levers 1 and 2 have slots 6 through which passes a pin 7 whereon a cam 8 is pivoted. The cam 45 has a lever 9.

The vertical members of the levers 1 and 2 have grooves 10 and 11 respectively, adapted to fit upon rods 12 and 13 respectively. Grooves 14 and 15, formed in the 50 filter frame 16, are adapted to receive the rods 12 and 13 respectively. The filter cloth 17 is interposed between the rods 10 and 11 and the grooves 14 and 15.

The cam 8 is adapted to bear upon the 55 crossbar 5.

The cloth 17 and the rods 12 and 13 hav-

ing been placed in position, the lever 9 is pushed downward in the direction shown by the arrow in Fig. 1, and the cam 8 bearing on the crossbar 5 forces upward the horizontal members of the levers 1 and 2, and as these levers are fulcrumed to the crossbar 5 their vertical members are forced inward and press upon the rods 12 and 13 so that a tight joint is made by the cloth 60 against the filter frame 16.

What I do claim and desire to secure by Letters Patent of the United States is:—

1. A clamping device, comprising in combination, a crossbar, bent levers pivoted on 70 said crossbar and having clamping arms lying opposite to each other and other arms arranged at the opposite side of said crossbar and substantially parallel thereto, with their inner ends adjacent to each other and 75 to the bar, and means carried by the adjacent ends of the last mentioned arms and co-acting with the crossbar to move said ends away from said bar to bring said clamping arms together.

2. A clamping device, comprising in combination, a cross bar, bent levers pivoted on said crossbar and having clamping arms lying opposite to each other and other arms of greater length arranged at the opposite 85 side of said crossbar with their inner ends adjacent to each other and to the bar, and means co-acting with said ends and said bar to move said ends away from the bar and to bring said clamping arms together 90 with increased pressure.

3. A clamping device, comprising in combination, a cross bar, bent levers pivoted on said crossbar and having clamping arms lying opposite to each other and other arms 95 of greater length arranged at the opposite side of said crossbar with their inner ends adjacent to each other and to the bar, and cam means carried by said ends and co-acting with said bar to move said ends away 100 from the bar and to bring said clamping arms together with increased pressure.

4. A clamping device, comprising in combination, a cross bar, bent levers pivoted on said cross bar having oppositely arranged 105 clamping arms and other arms lying adjacent said crossbar, and cam means carried by the last mentioned arms and co-acting with said cross-bar to move the clamping arms toward or away from each other. 110

5. A clamping device, comprising in combination, a cross bar, bent levers pivoted on

said crossbar having oppositely arranged clamping arms and other arms extending toward each other and overlapping at their ends, a pin passing through slots in the overlapping ends of the last mentioned arms, and a cam mounted on said pin and bearing against said cross bar.

6. A clamping device, comprising in combination, a cross bar, bent levers pivoted on said cross bar having oppositely arranged grooved clamping arms and other arms lying adjacent said cross-bar, clamping rods

lying in the grooves of the clamping arms, and means co-acting with the said other arms and the cross bar for moving the clamping arms toward or away from each other.

In testimony whereof I have signed my name to this specification in the presence of two witnesses.

CHARLES EDMUND CLEWS.
